PILOT-WIRE SUPERVISORY CIRCUITS

Myron A. Bostwick, Budd Lake, and Roy M. Smith, Livingston, N. J., assignors to Westinghouse Electric & Manufacturing Company, East Pittsburgh, Pa., a corporation of Pennsylvania

Application September 10, 1940, Serial No. 356,136

19 Claims. (Cl. 177—311)

Our invention relates to supervisory circuits for pilot wires, and particularly for pilot-wire systems which are utilized for the purpose of comparing the directions of current-flow at the two ends of an alternating-current transmission-line section which is being protected against faults within the protected section. The supervisory pilot-wire circuit has heretofore been utilized to circulate a small direct current which does not interfere with the operation of the transmission-line protective relays, the circulating direct current being utilized in the pilot wire for the purpose of "supervising" the pilot wire so as to respond to short-circuits, open-circuits, or a grounded conductor in the pilot wire. Such supervised pilot-wire systems are described and claimed in an application of M. A. Bostwick, Serial No. 278,845, filed June 13, 1939, patented March 10, 1942, Patent No. 2,276,150, and in a patent of E. L. Harder, No. 1,953,108, granted April 3, 1934, both assigned to the Westinghouse Electric & Manufacturing Company.

The principal object of our present invention is to improve upon supervisory pilot-wire circuits of the class described, by providing an indication of an accidental reversal of the pilot-wire connections, which, if undetected, would result in a faulty line-protecting relaying-operation, resulting in an erroneous tripping of the circuit-breakers in the transmission line, or a failure to trip such circuit-breakers during line-fault conditions. Such accidental reversal of the pilot-wire connections is particularly apt to be encountered on leased telephone circuits which are used for pilot-wire relaying, as the telephone company's service-men are not ordinarily aware of the importance of maintaining the correct pilot-wire polarity.

Other objects of our invention are to provide certain improvements in the operation of the supervisory pilot-wire circuits, particularly when said circuits are utilized for the transmission of intelligence-communicating signals or current-changes over the pilot wire for any auxiliary purposes other than pilot-fault supervision, as will be subsequently described.

With the foregoing and other objects in view, our invention consists in the apparatus, combinations, circuits, systems and methods hereinafter described and claimed, and illustrated in the accompanying drawing, wherein:

Figure 1 is a diagrammatic view of circuits and apparatus utilizing a polarized direct-current relay at the receiving end of a supervised pilot-wire system, for the purpose of detecting acci-

dental reversal of the pilot-wire connections; and Fig. 2 is a similar view of a supervised pilot-wire system utilizing a rectifier at the receiving end of the supervisory circuit for the purpose of detecting accidental reversal of the pilot-wire connections and also for the purpose of providing an automatic reduction in the direct-current resistance of the supervisory circuit when over-current intelligence-communicating signals are being transmitted over the pilot wire.

Our invention is illustrated, in both figures of the drawing, as being utilized in connection with a three-phase transmission-line section 3 which is provided with current-comparing pilot-wire 5 relay-protection. The particular system which is illustrated utilizes a line-fault-responsive phase-sequence relaying-apparatus HCB, at each end of the protected line-section 3, said apparatus including relay-contacts 4 for energizing the trip-circuit of a circuit-breaker 5 at that end of the protected line-section. The phase-sequence relaying-apparatus HCB may be of any suitable type for deriving a single-phase electrical quantity, either a voltage or current, which is responsive to the polyphase line-currents as supplied by line-current transformers 6, a suitable relaying-apparatus for this purpose being shown in the Harder Patent No. 2,183,646, granted December 19, 1939, and assigned to the Westinghouse Electric & Manufacturing Company.

The line-protecting relays HCB, besides being coupled to the line-current transformers 6, are also coupled to the respective primary windings 7 of two insulating transformers 8 having split secondary windings 9 and 10. The outer terminals of the split secondary windings 9 and 10 at the respective ends of the protected line-section are joined by a two-conductor pilot wire 12 to which our present invention is particularly directed, and the line-frequency currents are circulated in the pilot wire 12 through circuit-completing capacitors 13 and 14 which are utilized to join the inner ends of the respective split secondary windings 9 and 10 at the two ends of the pilot wire, respectively. The pilot wire 12 serves as a means for circulating and totalizing or comparing the line-frequency currents derived from the phase-sequence line-current-responsive apparatus HCB at the two ends of the protected line-section, so that the HCB relay-contacts 4 serve as means for protecting the line-section against faults therein.

The pilot wire 12 is supervised by means of a circulating direct current which is connected to the pilot wire across the terminals of the capaci-

5 tor 13 at one end of the pilot wire. The supervisory direct current is supplied from any suitable source such as a transformer 16 and a rectifier 17, the direct-current output-circuit of which is connected to the terminals of the capacitor 13 through the windings of a sensitive polarized relay 18 which has a front-contact 19 and a back-contact 20. The relay 18 is so chosen that, during normal pilot-wire conditions, the circulating supervisory direct current is of sufficient magnitude to keep the back-contact 20 open, without closing the front-contact 19, so that the relay will respond, either to an overcurrent produced by a short-circuit or a ground-fault on the pilot wire 12 or to an undercurrent caused by an open-circuiting or breakage of the pilot-wire circuit, in either event closing an alarm-circuit as indicated.

10 At the receiving end of the pilot wire 12, the capacitor 14 is shunted by a direct-current supervisory circuit, comprising a resistor 22 and an operating coil 23 of an undercurrent relay 24, having a back-contact 25 which energizes an alarm-circuit in response to an abnormal reduction in the circulated supervisory direct current 15 such as will occur whenever the pilot wire 12 was either short-circuited, open-circuited or grounded.

15 In accordance with our invention, means are, or may be, provided at the receiving end of the pilot wire, that is, across the terminals of the capacitor 14, for securing a selective action, with respect to the circulating direct current, according to the direction of said circulating direct current at said receiving end. In the particular form of embodiment of our invention which is shown in Fig. 1, this reversed-direction response is obtained by making the undercurrent receiver-end relay 24 a polarized relay, as illustrated, so that it will respond by "dropping out" and closing its back-contact 25, not only when the magnitude of the circulating current drops below a predetermined value, as in previous relay which have been utilized in such pilot-wire supervisory circuits, but also the polarized relay 24 will respond by "dropping out" and closing its back-contact 25 when the direction of the circulating current is reversed, even though the magnitude is not reduced below its normal value. The polarized relay 24 thus responds, by energizing an alarm-circuit, whenever there is an accidental reversal of the polarity of the pilot-wire connections.

20 In Fig. 2, instead of relying upon the polarization of the undervoltage receiving-end relay 24 to obtain a selective action in the event of a reversal of the supervisory-current direction, we utilize an auxiliary rectifier 26 in the supervisory direct-current circuit which is shunted across the terminals of the capacitor 14, said supervisory direct-current circuit including said auxiliary rectifier 26, the operating coil 27 of a combined overcurrent and undercurrent relay 28, and a resistor 29, although the relay 28 may be omitted, if it is not needed or desired, in any particular installation. The relay 28 has an undercurrent-responsive back-contact 31 which is utilized to energize an alarm-circuit as previously, and an overcurrent-responsive front-contact 32 which is adapted to be closed only in response to an abnormally large circulating direct current, as will be subsequently described.

25 In the system shown in Fig. 2, we have also shown means at the sending end for, at times, 75

predeterminedly increasing the magnitude of the circulating direct current in the pilot wire 12, such means being illustrated in the form of a resistor 33 and a shunting switch 34 for shunting some or all of the resistance 33, included in the direct-current output-circuit of the rectifier 17 which supplies direct current to the terminals of the capacitor 13 at the sending end of the pilot-wire supervisory circuit. When the switch 34 is closed, either manually or in response to any automatic operation whatsoever, an intelligence-transmitting impulse is sent over the pilot wire 12 in the form of an increased magnitude of the supervisory direct current. This increase in magnitude need not, and preferably will not, be sufficient to cause the sending-end polarized relay 18 to respond by closing its front-contact 19, but it will be sufficient to cause the receiver-end relay 24 to respond by closing its overcurrent make-contact 32, thus energizing an intelligence-receiving circuit which may be utilized to respond, in any desired way, to the intelligence which was transmitted by the closure of the switch 34 at the sending end of the supervisory circuit.

30 The intelligence-transmitting modulation of the circulating supervisory direct current, for the purpose of transmitting an impulse or impulses which can be used for tripping, metering or relaying of any kind, over the pilot wire, constitutes the subject-matter of the description and claims of a copending application of M. A. Bostwick, Serial No. 346,319, filed July 19, 1940. The addition of the auxiliary rectifier 26 to such a circuit is one of the features of our present invention.

35 It should be noted that a relatively large resistance 22-23 (Fig. 1), or 26-27-29 (Fig. 2), should be included in the supervisory pilot-wire circuit at the receiving end to aid in detecting high-resistance short-circuits which might occur on the pilot wire 12 close to said receiving end, that is, close to the end where the capacitor 13 is located, and opposite to the end where the direct-current source 16-17 and the capacitor 14 are located.

40 In accordance with our invention, particularly in the form shown in Fig. 2, where an intelligence-communicating over current signal is transmitted over the supervisory-current channel of the pilot wire 12, a type of auxiliary rectifier 26 should be utilized, having a considerable resistance to current-flow in the forward direction, as well as a very much higher resistance to current-flow in the reversed or backward or relatively non-conducting direction, so that the size of the resistor 29 may be reduced.

45 It is also extremely advantageous to choose a type of auxiliary rectifier 26 which automatically provides a considerable reduction in its forward-current resistance when traversed by currents larger than the normal circulated supervisory current, thus materially reducing the effective resistance of the entire supervisory-current circuit when the switch 34 is closed for the purpose of increasing the magnitude of the supervisory current. This desired automatic change in the resistance of the supervisory-current circuit, in response to abnormally large circulating direct currents, may be obtained by choosing, for the auxiliary rectifier 26, a high-voltage, low-current, contact-type rectifier, such as a copper-oxide rectifier, so that when the circulated direct current is changed from its normal value of, say, 2 milliamperes, to an increased value of anywhere from 2.3 milliamperes to 4 milliamperes or even

more, the effective resistance of the auxiliary rectifier 26 will be smaller than for the normal circulating direct current.

In the event of an accidental reversal of the pilot-wire connections, our system which is shown in Fig. 2 will operate by giving an undervoltage alarm-circuit signal at both ends of the pilot wire 12, as a result of the closure of both of the back-contacts 20 and 31 of the supervisory-circuit relays 18 and 28, respectively, said back-contacts 20 and 31 being closed because of the very great resistance of the rectifier 26 when an attempt is made to pass current in the wrong, or substantially non-conducting, direction therethrough. The provision for the energization of an alarm-circuit at the sending end as well as the receiving end of the supervised pilot-wire circuit is particularly advantageous in those systems where the receiving end of the supervised pilot wire is located in an unattended substation.

While we have illustrated and described our invention in two exemplary forms of embodiment, and while we have explained the essential principles of its operation as at present understood by us, we wish it to be understood that such illustration and explanation are intended by way of illustration and not altogether by way of limitation, as it is obvious that many changes may be made by those skilled in the art without departing from the essential spirit of our invention. We desire, therefore, that the appended claims shall be accorded the broadest construction consistent with their language.

We claim as our invention:

1. In combination, a protected alternating-current line-section, a pilot wire between the ends thereof, line-current-responsive means at each end of the pilot wire each deriving an alternating-current electrical quantity responsive to the line-current at its own end of the line-section, electrical-connection means for utilizing the pilot wire to totalize the derived electrical quantities from the respective ends, line-fault-responsive relaying-means for responding to the totalized quantities, means, including a direct-current source at a first end of the pilot wire, for circulating a direct current of a predetermined magnitude through said pilot wire, and means at the second end of the pilot wire for securing a selective action with respect to the circulating direct current according to the direction of said circulating direct current at said second end.

2. In combination, a protected alternating-current line-section, a pilot wire between the ends thereof, line-current-responsive means at each end of the pilot wire each deriving an alternating-current electrical quantity responsive to the line-current at its own end of the line-section, electrical-connection means for utilizing the pilot wire to totalize the derived electrical quantities from the respective ends, line-fault-responsive relaying-means for responding to the totalized quantities, means, including a direct-current source at a first end of the pilot wire, for circulating a direct current of a predetermined magnitude through said pilot wire, and a polarized undervoltage relay responsive to the circulating direct-current at the second end of the pilot wire.

3. In combination, a protected alternating-current line-section, a pilot wire between the ends thereof, line-current-responsive means at each end of the pilot wire each deriving an alternating-current electrical quantity responsive to the line-current at its own end of the line-section,

electrical-connection means for utilizing the pilot wire to totalize the derived electrical quantities from the respective ends, line-fault-responsive relaying-means for responding to the totalized quantities, means, including a direct-current source at a first end of the pilot wire, for circulating a direct current of a predetermined magnitude through said pilot wire, a rectifier serially included in the pilot wire at the second end thereof, and undervoltage direct-current relaying-means for responding to the circulating direct current.

4. In combination, a protected alternating-current line-section, a pilot wire between the ends thereof, line-current-responsive means at each end of the pilot wire each deriving an alternating-current electrical quantity responsive to the line-current at its own end of the line-section, electrical-connection means for utilizing the pilot wire to totalize the derived electrical quantities from the respective ends, line-fault-responsive relaying-means for responding to the totalized quantities, means, including a direct-current source at a first end of the pilot wire, for normally continuously circulating a direct current of a predetermined magnitude through said pilot wire at all times when said pilot wire is intact, means for, at times, predeterminedly increasing the magnitude of the circulating direct current in the pilot wire, a rectifier serially included in the pilot wire at the second end thereof, said rectifier having a lowered resistance at times of said predeterminedly increased direct-current flow, undervoltage direct-current relaying-means for responding to less than a predetermined magnitude of direct-current flow in the pilot wire, and overcurrent direct-current relaying-means for responding to said predeterminedly increased direct-current flow in the pilot wire.

5. In combination, a pilot wire extending between two spaced points, means, including a direct-current source at a first end of the pilot wire, for normally continuously circulating a direct current of a predetermined magnitude through said pilot wire at all times when said pilot wire is intact, means at the second end of the pilot wire for securing a selective action with respect to the circulating direct current according to the direction of said circulating direct current at said second end, means disposed at one point in the pilot wire for, at times, transmitting a distinctive intelligence-communicating current-change over the pilot wire, said distinctive intelligence-communicating current-change being of such nature as not to actuate said direction-responsive means, and means selectively responsive to said distinctive intelligence-communicating current-change for providing a predetermined response at another point in the pilot wire.

6. In combination, a pilot wire extending between two spaced points, means, including a direct-current source at a first end of the pilot wire, for normally continuously circulating a direct current of a predetermined magnitude and direction through said pilot wire at all times when said pilot wire is intact, a polarized undervoltage relay responsive to the circulating direct current at the second end of the pilot wire, means disposed at one point in the pilot wire for, at times, transmitting a distinctive intelligence-communicating current-change over the pilot wire, said distinctive intelligence-communicating current-change being of such nature as not to actuate said direction-responsive means, and means selectively responsive to said distinctive

intelligence-communicating current-change for providing a predetermined response at another point in the pilot wire.

7. In combination, a pilot wire extending between two spaced points, means, including a direct-current source at a first end of the pilot wire, for normally continuously circulating a direct current of a predetermined magnitude through said pilot wire at all times when said pilot wire is intact, a rectifier permanently serially included in the pilot wire at the second end thereof, undercurrent direct-current relaying-means for responding to the circulating direct current, means disposed at one point in the pilot wire for, at times, transmitting a distinctive intelligence-communicating current-change over the pilot wire, said distinctive intelligence-communicating current-change being of such nature as not to actuate said direction-responsive means, and means selectively responsive to said distinctive intelligence-communicating current-change for providing a predetermined response at another point in the pilot wire.

8. In combination, a pilot wire extending between two spaced points, means including a direct-current source at a first end of the pilot

wire, for normally continuously circulating a direct current of a predetermined magnitude through said pilot wire at all times when said pilot wire is intact, means for, at times, predeterminedly increasing the magnitude of the circulating direct current in the pilot wire, a rectifier serially included in the pilot wire at the second end thereof, said rectifier having a lowered resistance at times of said predeterminedly increased direct-current flow, undercurrent direct-current relaying-means for responding to less than a predetermined magnitude of direct-current flow in the pilot wire, and overcurrent direct-current relaying-means for responding to said predeterminedly increased direct-current flow in the pilot wire.

9. The invention as defined in claim 3, characterized by said undercurrent direct-current relaying-means being at the first end of the pilot wire.

10. The invention as defined in claim 7, characterized by said undercurrent direct-current relaying-means being at the first end of the pilot wire.
